UNITED STATES PATENT OFFICE.

GEORGE T. RONK, OF DES MOINES, IOWA, ASSIGNOR TO SPEEDER MACHINERY CORPORATION, OF FAIRFIELD, IOWA.

GIRDER CONSTRUCTION FOR EXCAVATORS.

Application filed March 24, 1924. Serial No. 701,518.

To all whom it may concern:

Be it known that I, GEORGE T. RONK, a citizen of the United States, and a resident of Des Moines, in the county of Polk, State 5 of Iowa, have invented a certain new and useful Girder Construction for Excavators, of which the following is a specification.

This invention relates to improvements in frame constructions for excavators of that 10 type illustrated in my co-pending application filed January 11, 1922, Serial Number 528,587, on an excavating machine.

The object of my invention is to provide a new and improved frame construction for 15 that type of excavators which employ a truck and an excavator carrying frame pivoted to swing in a horizontal plane above the truck, said pivoted frame being designed to carry a boom and drums for actuating 20 the boom, and a shovel.

More specifically it is the object of my invention to construct the boom and drum supporting frame of stock material such as 25 I-beams and plates, the same being riveted and secured together in such a manner as to form a frame of light weight and inexpensive construction which will support the necessary operating mechanism, and at the same time be very rigid.

30 My invention consists in the construction, arrangement and combination of the various parts of the device, whereby the objects contemplated are attained, as hereinafter more fully set forth, pointed out in my 35 claims, and illustrated in the accompanying drawings, in which:

Figure 1 is a side elevation of an excavator truck of the type to which my improvement is related, showing mounted thereon my 40 proved excavator supporting frame, and also illustrating part of the mechanism which is designed to be carried by the said frame.

Figure 2 is a central longitudinal sectional view of a portion of the frame.

45 Figure 3 is a transverse sectional view taken on the line 3—3 of Figure 2.

The numeral 10 indicates a truck frame provided with supporting and steering wheels 11 and tractor wheels 12. The 50 tractor wheels 12 are provided with sprocket wheels 13 designed to carry chains 14 driven by means of sprocket pinions 15. The pinions 15 are mounted on a countershaft 16 rotatively mounted in bearings 17 from the under side of the frame 10.

The frame 10 comprises a series of longitudinally extending I-beams of which there are preferably four in number. The I-beams 18 are designed to support a pivot post 19. A circular internal gear 20 is 60 supported on top of the frame 10 concentric with the support 19 having an outwardly extending flange 21.

My improved frame comprises a pair of I-beams 22 of considerable length and spaced apart and parallel with each other. The under faces of the I-beams 22 are provided with a plate 23, and the upper faces provided with a plate 24. On top of the plate 24 and vertically above each of the members 70 22 I have provided an I-beam 25, the said I-beam being shorter than the I-beams 22. The bottom flanges of the I-beam 25, the plate 24 and the top flanges of the I-beams 22 are secured together by suitable rivets 26, 75 while the plate 23 is secured to the bottom flanges of the I-beams 22 by rivets 27.

The upper flanges of the beams 25 are designed to carry a series of journals 28, 29 and 30. The journals 29 are designed to 80 receive a shaft 31, the central portion of which is provided with a beveled gear 32. The shaft 31 is provided with a belt wheel 33. The beveled gear 32 is designed to mesh with a beveled gear 34 mounted on the 85 upper end of a vertically arranged shaft 35 pivotally mounted in the plates 23 and 24. A gear 36 is splined with the said shaft and is designed to be moved into and out of engagement with a second gear 37 90 mounted on a vertically arranged shaft 38, which is also pivotally mounted in the plates 23 and 24. The said shaft 38 is also rotatively mounted in the pivot support 19 and has its lower end provided with a 95 beveled gear 39, which in turn meshes with the beveled gear 40 on the shaft 16.

A third vertically arranged shaft 41 is also pivotally mounted in the plates 23 and 24 and is designed to carry a gear 42 which 100 may also be engaged by the gear 36. The lower end of the shaft 41 is provided with a pinion 43 designed to mesh with the teeth of the gear 20. The beams 22 and the plate 23 are designed to carry roller supporting brackets 44 having rollers 45 designed to travel on the flange 21 of the gear 20. Each of the shafts 28 and 30 is provided with spur gears 45 and 46 designed to mesh with a spur gear 47 on the shaft 29. The shafts 105 110

28 and 30 are also designed to carry cable drums 48. A boom 49 is secured to one end of the members 22, while an engine 50 is supported on the opposite end, the belt wheel 5 33 being driven by means of the belt 51 from the said engine.

The above gearing devices have been described and illustrated simply for the purpose of more clearly illustrating the purpose to which my frame construction is adapted. It will be seen that when the various mechanisms have been operated and the shaft 29 is rotated, the vertical shaft 35 will also be rotated, and that the truck may 10 be advanced forwardly by simply shifting the gear 36 into engagement with the gear 37, or if it is desired to rotate the frame 22 above the frame 10, the gear 36 is moved into engagement with the gear 42 or the 15 gear 36 may be moved to throw both of said mechanisms out of operation. Either of the drums 48 may be actuated independently by mechanism not illustrated.

It will be seen that when the various 20 mechanisms mentioned have been set into operation, a considerable amount of strain is thrown onto the frame members in various directions and at various angles.

It will also be seen that by the construction herewith illustrated, a rigid frame has 25 been provided of cheap and light construction, which will carry the various mechanisms without breaking or twisting.

I claim as my invention:

30 1. An excavator frame comprising spaced and parallel I-beams having the webs of said I-beams arranged vertically, a plate riveted to the lower flanges of said I-beams, a second plate on top of said I-beams, an I-beam on top of said plate and above each 35 of the first said I-beams and in a common plane therewith, the lower flanges of the top I-beams and the upper flanges of the lower I-beams being rigidly secured together and to said second plate.

2. An excavator frame comprising spaced and parallel I-beams having the webs of said beams arranged vertically, a plate riveted to the lower flanges of said I-beams, a second plate on top of said I-beams, a pair of I-beams on top of the last said plate parallel with the first said I-beams, the flanges of the top I-beams and the upper flanges of the lower I-beams being rigidly secured to said plate, a series of journals for the upper flanges of said upper I-beams, and a series of shafts extending vertically through the 50 said plates.

3. An excavator frame comprising a pair of spaced and parallel I-beams, having their webs in vertical planes, a plate secured to the under side of said I-beams, a plate secured on top of said I-beams and above the first said plate, an I-beam on said top plate above each of the first said I-beams and parallel therewith, means for supporting a series of horizontally arranged shafts on the top plate of said top I-beams, and means for supporting a series of vertically arranged shafts in said plates, one end of said frame 55 being designed to carry a boom and the opposite end an engine.

4. A truck, an excavator frame comprising a pair of spaced and parallel I-beams, having their webs in vertical planes, a plate secured to the under side of said I-beams, a plate secured on top of said I-beams and above the first said plate, an I-beam on said top plate above each of the first said I-beams and parallel therewith, means for supporting a series of horizontally arranged shafts on the top plate of said top I-beams, means for supporting a series of vertically arranged shafts in said plates, one end of 60 said frame being designed to carry a boom and the opposite end an engine, and means for revolvably supporting said excavator frame above said truck.

GEORGE T. RONK.
